UNITED STATES PATENT OFFICE.

EDWARD E. SPIEGEL, OF NEW YORK, N. Y.

CLOTH-MEASURING MACHINE.

Application filed August 5, 1927. Serial No. 210,800.

This invention has reference to mechanism for measuring fabrics in the web form, at the same time giving the opportunity to inspect the fabric as it passes between the supply roll and the winding roll.

One of the objects of the invention is to provide means in such an apparatus to facilitate operation on a tubular fabric, such as is produced on a knitting machine or similar mechanism, and which includes means for keeping the fabric properly spread in flat form of double thickness, as it is wound.

A further object is to provide improved means for causing the length of the fabric to operate a register, as it passes to the winding-up roll, whereby the total length of the web will appear on the register when it has been wound.

Another object of the invention is to provide improved means for controlling the machine, that is particularly designed to cause the web to pass over a suitable area for inspection by the operator, during the winding operation, so that any defects in the web can be readily discovered, and the operator can instantly arrest the winding mechanism, when such condition is discovered.

A further object of the invention is to provide means for operating on webs of different widths.

In the accompanying drawings showing one embodiment of my invention:

Fig. 1 is a front view of the machine.

Fig. 2 is a rear view.

Fig. 3 is a side elevation.

Fig. 4 shows enlarged the details of the winding rolls and adjacent parts.

Fig. 5 shows the adjustable guides for the web.

Fig. 6 is another view of the rolls and spreader.

Fig. 7 shows the spreader form separately.

Fig. 8 is a detail of the power control.

As shown in the drawings, the machine is in the form of an open frame denoted generally by 9 that supports a kind of table 10. At the front of the machine is a supply roll 11, carried on uprights 12, 12, and readily detached therefrom, shown with a roll 13 of fabric wound thereon. The end of the fabric is passed upwardly around a guide roll 14 carried by posts 15, 16, suitably mounted on the table, with a roll 17 at the top, around which the web is passed. A

guide roll 18 is mounted on uprights 19—19, on the table a short distance beyond the posts, around which the web 13 is brought down, and passed forward to the feed and winding rolls. The operator standing at the front end of the machine can inspect the web as it passes upwardly from the supply roll, to and around the upper guide roll 17. The winding and feed rolls are at the rear of the table, mounted between upright posts 20 and 21. A pair of feed rolls 22 and 23 are shown one above the other carried by these two posts, between which the web is passed, and the lower roll, or both of them are of a certain predetermined circumference, such as one half of a yard. These rolls are preferably covered with fabric. When the web is drawn between these rolls by their rotation, for each revolution of the lower roll a half yard of the web is advanced, that is indicated by a suitable register mechanism, well known in this art. A counter is indicated at 24 that will show the revolutions of these rolls, being connected with the lower roll 22 in such a manner that a large number of rotations will be indicated, and which, by the various disks, may also indicate fractions of a revolution.

A friction winding roll 25 is shown mounted to rotate in the posts 20 and 21 at its ends, which latter have a vertical movement in the grooved inner wall 28 of each of these posts. This roll 25, or the web wound thereon, will be free to move downwardly to contact with the upper feed roll 23. The web 13, after passing rearward from the guide roll 18, is caused to travel between the two feed rolls 22 and 23, suitably driven in the proper directions as indicated by the arrows; and the end of the web, after passing between these rolls to the rear, is secured to the winding roll 25 by suitable means. It will be understood that the rolls 22 and 23 being driven by suitable means, will by the engagement of the web and on the roll 25, serve to turn this roll and wind up the web thereon, and as the diameter of this winding roll increases from the accumulation of the layers of fabric thereon, the roll 17 itself will move upward in its slotted guide at the ends, in the posts. While the surface area of this winding roll will increase with its thickness, relative to the rolls 22 and 23, the surface speed of the latter rolls will be constant, and the register will properly show

the length of the web that passes between these rolls, and as accumulated on the winding roll 25.

Suitable means are provided for driving these feed rolls. They are shown provided with meshing gears 27 and 28 respectively, on the shafts 29 and 30 of the rolls, and the latter shaft carries a grooved pulley 31. This pulley is driven by a belt 32, from pulley 371 on a shaft 33 carried by brackets 34 and 35, on a suitable cross frame 36, at the lower part of the frame. This shaft 33 is shown having a pulley 37 secured thereto, which may be driven by belt 38 from wide pulley 39, fast on a cross shaft 40. The latter carries a pulley 41 shown as driven by a belt 42, from pulley 43 on a suitable electric motor 44. The latter may have a usual control box and lever 45 adjacent the front, whereby the operator can stop and start the motor. On the shaft 33 is a loose pulley 46 adjacent the tight pulley 37, so that the belt 38 can be suitably shifted from one pulley to the other, still engaging the wide driving pulley 39, which will serve to engage and free the feed rolls. A shaft 47 on the base or floor carries an arm 48, that engages a slide 49 which carries a belt engaging fork 50. The shaft 47 also carries a foot lever or pedal 51, that will rock this shaft when moved down, and swing the rod and belt shifter to move the belt from the tight pulley to the loose pulley that will cut off the power from the feed rolls. This movement will compress a spring 52 adjacent the arm 48 that tends to retain the belt shifted onto the tight pulley. When the pedal 50 is thus moved down, it will engage a detent 53 that will hold it depressed with the belt shifted to the loose pulley. It will be seen that when the detent is kicked off by the operator, the spring 52 will cause the belt shifter to move the belt. Means are further provided in connection with this foot control to act as a brake and very quickly arrest the rotation of the feed rolls, so that the operator on discovering an imperfection in the web, or should it be desired to quickly stop the winding, the feed rolls are at once arrested. On the shaft 49 is placed a brake shoe 54, that when the pedal is depressed and the shaft 49 carries the belt shifter to move the belt to the loose pulley, will be brought into engagement with the side of the driving pulley 37, see Fig. 8. This will at once arrest the pulley 37 and stop the feed rolls. When the pedal is released and the spring again shifts the pulley, the brake arm will release the tight pulley.

In winding the tubular fabric, it is desirable or necessary to keep it properly spread out or distended because of the two thicknesses and the doubled edges. Means are provided for keeping the double web properly spread out, shown in the form of

a spreading frame, indicated separately in Fig. 7. This may comprise a rod or cylinder 55 with a small rod having the end portions 56 and 57 secured to the cylinder to provide an opposite length 58 parallel to the cylinder 55. This frame can be provided in different lengths to accommodate the length between the ends 56 and 57, permitting the insertion of this frame with these ends in engagement with the two doubled edges, as indicated in Fig. 6, that will keep the fabric spread out in proper form for winding. This frame is inserted in the web end before it is passed between the feed rolls 22 and 23, and it is mounted in this position, just beyond these feed rolls by a suitable support, such as a cross plate 59 suitably supported as by a bracket 6 extending across a short distance in front of the feed rolls 22 and 23. In operation the frame carried inside of the web, will have the end portions 56 and 57 of the frame and the web portions adjacent thereto on the lower side, resting upon this plate 59, with the cylinder portion 55 that is larger and projects beyond the end rod portions 55 and 57, overhanging the front edge of this plate, see Fig. 3. The feed rolls 22 and 23 being close together and separated in use by the small thickness of the double fabric, will not serve to draw the frame or the cylinder 55 in between the rolls, but will keep it in this position in which it serves to keep the tubular fabric properly spread. It will be understood that this guide plate 59 will serve to accommodate different widths of web up to the full width of the rolls 22 and 23, and corresponding sizes of the spreaders employed.

Means are further provided for guiding the web at its edges, so that it will wind up uniformly any length on the winding roll, and which guide means preferably engages the ends of the spreader so that it cannot shift lengthwise and cause side movement of the web, and this means is preferably adjustable for different widths fabrics, and different spreader lengths.

As shown I provide a cross shaft with screw threaded portions 61 and 62, having right and left hand threads thereon; which portions engage similarly threaded arms 63 and 64 that slide on a guide rod 65. These arms carry guide portions or rolls 66 and 67 respectively, that are brought adjacent the ends of the spreader inside of the web. Turning the shaft 60 by an arm 69, will move these arms, either both toward each other, or in the opposite direction, at equal distances from the middle of the rolls, and thus the guides can be shifted to accommodate the web where engaged by the spreader.

It will be obvious that the same apparatus can be used to rewind or transfer a fabric that is plain instead of tubular, the spreader simply being omitted, and the

fabric passed through the several parts of the machine from the supply roll 11 to the winding roll 25.

In the use of the machine, the supply roll 13 on the roll or shaft 11 is mounted on the posts 15, 16, and the web is passed up over the top roll 17, then down around the guide roll 18, and if a tubular web, the frame is inserted in this end, that is then passed between the feed rolls 22 and 23, the spreader resting on the supporting plate 59, with the larger cylinder of this frame overhanging this cross plate, adjacent the feed rolls. The end of the web passes between these feed rolls and brought up and secured to the winding roll 25 whereby the latter with the wide portion thereon will rest on top of the pulley roll 23. The side guide rolls 66 and 67 are adjusted by the arm 69 to be brought adjacent the web where it encloses the spreader. The register 24 is now set at zero, and the operator can swing the switch to start the motor, and then the pedal 51 is released from the trip arm 53, that will cause the belt shifter by its spring to move the belt to the tight pulley. This will cause rotation of the feed rolls 22 and 23, and the latter will turn the winding roll 25 to wind up the web thereon, that is drawn from the supply roll 13, passing over the said guide rolls. The operator standing at the front of the machine will have a considerable area of the fabric spread out before him, and can detect any imperfections in the same. At any time he can press down the pedal that will shift the belt and also apply the brake, that will at once arrest the feed rolls. When the web becomes entirely wound on the roll 25, the machine is stopped and the register at 24 will indicate the exact length of the web that has been rewound on this roll 25. With plain fabrics the operation is the same, but the spreader is not used, and the guide rolls 66 and 67 are brought adjacent the edges of the web. Obviously this web will be indicated in the same manner.

What I claim is:

1. In a device for winding fabric webs, a pair of upper and lower feed rolls arranged to draw the web between them by their relatively opposite rotations, a winding roll arranged to have the end of web secured thereto and resting by its weight on top of the upper roll to be turned thereby with guiding means to permit upward movement as such winding roll becomes covered by the cloth.

2. In a device for winding fabric webs, a pair of upper and lower feed rolls arranged to draw the web between them by their relatively opposite rotations, a winding roll arranged to have the end of web secured thereto and resting by its weight on top of the upper roll to be turned thereby

with guiding means to permit upward movement as such winding roll becomes covered by the cloth, and a counter connected with the said feed rolls to register the length of the web according to the surface of the roll engaged by the web.

3. In a device for winding tubular fabric webs, feed rolls to draw the web, a spreader device comprising a flat frame that is placed inside of the tubular web adjacent the rolls, and means arranged to support the said frame in proximity to the said rolls to cause the cloth to pass around the frame and into the rolls in a properly spread condition.

4. In a device for winding tubular fabric webs, a winding roll and feed rolls connected therewith to draw the web, a spreader device comprising a flat frame that is placed inside of the tubular web adjacent the rolls, a cross plate adjacent the rolls arranged to support the said frame in proximity to the said rolls to permit the web to pass around the frame and into the rolls in a flat spread condition.

5. In a device for winding tubular fabric webs, feed rolls to draw the web, a spreader device comprising a comparatively small cylinder with a rod smaller than the cylinder bent at the ends and secured to the cylinder to form therewith an oblong rectangle of a length at the two rod ends for insertion in the tubular web for proper spreading of the web, and means to support the frame in proximity to the said rolls to permit the cloth to pass around the frame and into the rolls in a proper spread condition.

6. In a device for winding tubular fabric webs, feed rolls to draw the web, a spreader device comprising a comparatively small cylinder with a rod smaller than the cylinder bent at the ends and secured to the cylinder to form therewith an oblong rectangle of a length at the two rod ends for insertion in the tubular web for proper spreading of the web, and means to support the frame in proximity to the said rolls to permit the cloth to pass around the frame and into the rolls in a proper spread condition, said frame resting by its rod ends on the cross plate with the cylinder overhanging the edge of the plate in proximity to the feed rolls.

7. In a device for winding tubular fabric webs, feed rolls to draw the web, a spreader device comprising a flat frame that is placed inside of the tubular web adjacent the rolls, means arranged to support the said frame in proximity to the said rolls to cause the cloth to pass around the frame and into the rolls in a proper spread condition, upright guide rolls adjacent the ends of the frames with means for adjusting them together toward and from each other to accom-

modate different lengths of frames for different fabric widths.

8. In a device for winding tubular fabric webs, feed rolls to draw the web, a spreader device comprising a comparatively small cylinder with a rod smaller than the cylinder bent at the ends and secured to the cylinder to form therewith an oblong rectangle, of a length at the two rod ends 10 for insertion in the tubular web for proper spreading of the web, a cross plate to support the frame in proximity to the said rolls to permit the cloth to pass around the frame and into the rolls in a proper spread condition 15, said frame resting by its rod ends on the cross plate with the cylinder overhanging the edge of the plate in proximity to the feed rolls, upright guide rolls adjacent the ends of the frame, with means for adjusting them together toward and from each other to accommodate different lengths of frames for different fabric widths.

9. In a device for winding fabric webs, a pair of upper and lower feed rolls arranged 20 to draw the web between them by their relatively opposite rotation, a winding roll arranged to have the end of web secured thereto and resting by its weight on top of the upper roll to be turned thereby with guiding 25 means to permit upward movement as such winding roll becomes covered by the cloth,

upright guide rolls adjacent the ends of the frame, with means for adjusting them simultaneously toward and from each other to accommodate different lengths of frames for 35 different fabric widths.

10. In a device of the character set forth, the combination with the feed rolls, and a winding roll, of a motor shaft with means for driving the shaft, and a device in the 40 driving means arranged to connect and free the shaft, a foot lever on the base, and a brake connected with the foot lever, whereby the device can be opened and the brake 45 at once applied to arrest the winding rolls.

11. In a device of the character set forth, the combination with the feed rolls and a winding roll, of a motor shaft arranged to drive the shaft and a wide pulley, a shaft carrying a fast and a loose pulley a belt connecting said latter pulleys with said side pulley to be shifted onto either pulley means for driving the feed rolls from said fast pulley, a foot lever a spring shaft a belt and the fast pulley on the rolls, said foot lever when depressed serving to compress the spring and to shift the belt to the loose pulley, and a detent arranged to hold the foot lever depressed with the belt on the loose pulley.

Signed at New York, N. Y., on July 30, 50
1927.
